UNITED STATES PATENT OFFICE.

WILLIAM B. RHOADS, OF SAN FRANCISCO, CALIFORNIA.

COPY-HOLDER.

1,245,027.

Specification of Letters Patent.

Patented Oct. 30, 1917.

Application filed June 8, 1916. Serial No. 102,468.

To all whom it may concern:

Be it known that I, WILLIAM B. RHOADS, a citizen of the United States, and a resident of the city and county of San Francisco, State of California, have invented a new and useful Copy-Holder, of which the following is a specification.

My invention relates to means for holding data which is to be copied.

10 An object of my invention is to provide a copy holder in which the indicator is returned automatically from the bottom to the top of the copy.

Another object of my invention is to provide a copy holder which may be folded about the machine to which it is attached.

Another object of the invention is to provide a copy holder in which the indicator is adjustable to different thicknesses of the 20 copy pad.

Another object of the invention is to provide a copy holder which is attachable to typewriters, linotypes, monotypes and similar machines and in which an indicator 25 is moved a predetermined amount by depressing a key.

Another object of the invention is to provide a copy holder in which the spacing movement of the indicator is adjustable to 30 correspond with the spacing of the lines of the copy.

The invention possesses other features of advantage some of which, with the foregoing, will be set forth in the following description of the preferred form of my invention which is illustrated in the drawings accompanying and forming part of the specification. It is to be understood that I do not limit myself to the showing made 40 by the said drawings and description, as I may adopt variations of the preferred form within the scope of my invention as set forth in the claims.

Referring to the drawings:

45 Figure 1 is a side elevation of my copy holder, showing its application to an ordinary typewriter.

Fig. 2 is a front elevation of the copy holder apart from the typewriter.

Fig. 3 is a fragmentary view on an enlarged scale of a portion of my device.

Fig. 4 is a detail on an enlarged scale showing a portion of the mechanism.

Fig. 5 is a fragmentary sectional view taken on the line 5—5 of Fig. 3.

Fig. 6 is a detail on an enlarged scale showing a portion of the mechanism.

Fig. 7 is a section taken on the line 7—7 of Fig. 6.

The copy holder of my invention is applicable in any circumstances in which it is desired to maintain the matter which is to be copied in a convenient position before the eyes of the copyist, but in this application, I will show and describe my invention as it is used in connection with a typewriter.

My invention includes a frame comprising the upright members 2, and the member 3 which is adapted to be rigidly secured to a typewriter, preferably by clamp members 4 and 5. The exact manner of securing this frame to the frame of the typewriter is not important. The essential thing is that it shall be rigidly secured to the typing machine and in effect an integral portion thereof.

The copy holder in which the copy is retained is pivotally mounted upon the frame 2—2 so that it may be folded down over the top of the typing machine when the latter is closed up in its desk. The copy holder preferably consists of a thin, metallic plate 7 and having a ledge 8 at its lower front edge. At the lower rear edge of the plate 7 a sleeve 9 is mounted on brackets 12 and 13 which securely attach the sleeve to the plate. On the outside of the brackets the sleeve extends a short distance and these extensions form journals, bearings for which, 14, are arranged at the top of the frame members 2. The plate 7 is therefore adapted to be turned in the bearings 14, and a stop 15 is arranged on one of the frame members 2 to limit the backward turning of the plate.

Arranged in the sleeve 9 is a shaft 16, and a spring 17, coiled about the shaft and attached at one end to the sleeve and at the

other end to the shaft, resists the turning of the shaft in the sleeve. Fixed to the outer end of the shaft 16 is a sprocket wheel 19 and a ratchet 21. A U-shaped member 24 is disposed upon the side of the plate 7 above the sprocket 19. At the top of this member is mounted another sprocket 25 and a chain 26 passes about the sprockets, its front reach 26^a being disposed in the member 24 which therefore acts as a channel or guide in which the front reach of the chain 26 slides when the lower sprocket 19 is turned.

Means are provided for turning the ratchet wheel intermittently through a certain arc of revolution. A rocker 28 is loosely mounted upon the end of the shaft next to the ratchet 21. The rocker is retained in position by means of the washer 31 bearing against a shoulder on the shaft and the thumb nut 33 threaded on the shaft tight against the washer. The rocker is oscillated by means of the link 35 pivoted thereto and to a lever 36 pivotally mounted at 37 upon the frame extension 38. The forward end of the lever 36 carries a key 39 preferably suitably designated, and disposed adjacent the typewriter bank of keys in a conveniently reached position. A spring 41 operates to return the lever and rocker to normal position after each depression of the key, and a stop or loop 42 through which the lever passes limits the maximum movement of the lever. The rocker 28 carries a pawl 44 which is retained in engagement with the teeth of the ratchet 21 by the spring 45. The teeth of the ratchet, and the rocker are so disposed that depression of the key 39 effects a movement of the ratchet in a direction such that the travel of the outer reach of chain 26^a in the channel 24 is from the top toward the bottom of the plate 7.

Means are provided for varying the amount of movement of the ratchet when the key is depressed. A portion 47 of the channel 24 is extended rearwardly between the sprocket 19 and the ratchet 21. Preferably it encircles the shaft and is of circular form slightly larger than the ratchet 21. On the shaft 16 between the plate 47 and the ratchet 21 is loosely disposed a disk 51 preferably about the same size as the plate 47. Several holes are formed in the disk 51 on a circle concentric with the shaft 16 and a spring pressed knob 52 carried by the plate 47 is adapted to engage in these holes so that the disk is prevented from rotating unless a certain amount of pressure is exerted to turn it; when the knob 52 is disengaged from the hole in which it happens to be lying. A portion of the edge of the disk 51 is formed with a flange 54 which extends across the teeth of the ratchet 21. The

flange is so placed that in a portion of the recovery movement of the rocker 28 the pawl 44 rides up upon the flange and is therefore drawn out of engagement with the teeth of the ratchet. By varying the position of the flange the pawl 44 may be kept in contact with it for various proportions of the operating movement of the rocker and allowed to engage the ratchet only for the balance of the movement. The spacing and position of the holes in the disk 51 are such that the disk, and hence the flange, is held in predetermined relation to the movement of the rocker so that the amount of movement imparted to the ratchet 21 by the rocker may be controlled as desired. At the front, the disk is provided with a pointer 56, which in conjunction with a scale 57 fixed upon the lower end of the channel provides means for determining the position of the disk. The disk 51 is provided with an ear 58 which serves as a handle for shifting it. A spring 85 pressed pawl 61 pivoted to the side of the channel engages the ratchet 21 on the recovery movement of the rocker 28 and prevents the spring 17 from turning the shaft, sprocket and chain back to first position. Slidably arranged upon the front of the channel 24 is a block 64. The block is attached to the chain 26^a on the inside of the channel through a slot disposed in the front face of the channel and any movement of the chain 26 upon the sprockets is accompanied by a corresponding movement of the slide block. Hinged upon the block 64 between the lugs 65 thereon is a socket 66 and in the socket is arranged a line indicator 67 which overlies the plate 7 and any copy which is held thereon. Preferably the indicator is provided with graduations similar to those on the spacing guide on the front of the typewriter. The indicator is preferably reversible in the socket to accommodate a very thick copy pad thereunder. A spring 69 tends to turn the socket inwardly, thus keeping the indicator pressed against the copy. When there is need, the indicator may be swung outwardly about its pivotal mounting in the block against the resistance of the spring 69.

Preferably the parts are so disposed that when the indicator is in its topmost position there is a slight tension in the spring 17. It is now apparent that successive depressions of the key 39 effect intermittent rotation of the ratchet and shaft and intermittent movement of the chain 26^a and the attached indicator, the latter moving from the top of the plate 7 toward the bottom in steps determined by the effective throw of the rocker 28 which as already explained is determined by the setting of the disk 51. If the disk is set to "1" on the scale, each

depression of the key lowers the indicator one line space. If the disk is set to "3" on the scale, the key drops the indicator three line spaces with each depression. With the 5 copy on the plate, it is therefore necessary only to set the disk for the spacing of the copy. A depression of the key when a line is finished moves the indicator to the next line.

- 10 Means are provided for automatically returning the indicator to the top or first position when the limit of its advance across the copy support 7 is reached. The lower part of the block 64 is provided with a slanting surface 72 and the pawl 61 is provided with a roller 73 mounted on a pin rigidly fixed in the pawl. The roller extends across the channel 24 in a position to be engaged by the wedge surface 72 when the indicator 15 is at its lowest point. As the wedge passes under the roller, the latter is forced up, and the pawl 61 freed from the ratchet 21. A spring pressed latch 74 is arranged above the pawl 61 and as the pawl is lifted out of 20 engagement with the ratchet, the latch catches and holds the pawl in the disengaged position. Except for the engagement of the pawl 44 on the rocker, the spring 17 would now cause a recovery movement of 25 30 the shaft and chain, carrying the indicator back to the top of the plate, and this occurs as soon as the pawl 44 is lifted off of the ratchet by the flange 54 during the recovery movement of the rocker which leaves the 35 shaft free to rotate. A rubber stop 75 at the top of the channel 24 receives the impact of the upwardly moving block 64 and makes the recovery practically noiseless. In order to release the latch 74 from the pawl, so that 40 45 the pawl may again engage the ratchet on the downward movement of the indicator, a trip 76 is secured to the chain at a point which will engage the pin 77 and release the latch just as the indicator reaches its top position. The pawl 61 is provided with a short projecting rod 78 whereby it may be disengaged from the ratchet by the fingers at any time.

The top of the copy support 7 is provided 50 with a clamp for holding the copy. The clamp preferably consists of a rod 81 pivotally mounted at its ends and offset between the ends, so that different thicknesses may be held by it. Preferably rubber friction 55 pads 82 are provided on the offset portion. The clamp is pressed against the work by means of a spring 83 arranged at one end of the rod 81.

If it is desired to backspace the indicator, that is, set it back to a higher line, the pawl 61 is moved out of engagement with the ratchet wheel, the thumb nut 33 being frictionally engaged by the fingers and

thumb, so that the backward rotation of the shaft and sprocket may be controlled. The 65 nut 33 and attached shaft is allowed to turn in the fingers until the indicator reaches the desired height, where it is stopped and the latch 74 released from the pawl which then engages the ratchet and prevents further 70 backward movement.

It will be understood from the above explanation that the plate 7 may be folded down over the machine about an axis coincident with the axis of the shaft 16 and for 75 this reason, none of the working parts are disarranged or need to be detached because of said folding.

In case it is desired to start the feed of the indicator from a point below its topmost 80 position, the thumb wheel or nut 33 may be rotated by the fingers to bring the indicator to the desired position.

I claim:

1. In a copy holder, a frame, a copy support mounted on said frame, an indicator overlying said copy support, means for advancing said indicator across said copy support, means for returning said indicator to first position, and means for automatically effecting the operation of said last-named means. 85 90

2. In a copy holder, a frame, a copy support mounted on said frame, an indicator overlying said copy support, means for advancing said indicator across said copy support, means tending to return said indicator to first position, means for holding the returning means inoperative, and a trip for rendering said last-named means inoperative at the point of maximum advance of 95 100 said indicator.

3. In a copy holder, a frame, a copy support mounted on said frame, an indicator overlying said copy support, means for advancing the indicator across said copy support, means including a shaft for automatically returning the indicator to first position, said copy support being pivoted upon said frame about the axis of said shaft and 105 110 means arranged upon said indicator-advancing means for effecting the operation of said automatic returning means.

4. In a copy holder, a copy support, an indicator overlying said copy support, 115 means for advancing the indicator across said copy support, means for returning said indicator to first position, means for holding the returning means inoperative and a trip arranged upon said indicator-advancing 120 means for releasing said holding means.

5. In a copy holder, a copy support, an indicator overlying said copy support, a spring interposed between said indicator and said copy support, means for advancing the indicator across said copy support 125

and coincidently placing said spring under tension, means for retaining said spring under tension, and means mediateley connected to said indicator and movable therewith for releasing said retaining means.

5. In a copy holder, a frame, a copy support mounted on said frame, an operating key arranged upon said frame, an indicator arranged to move across said copy support, means mediateley connecting said key and said indicator, whereby movement of the key effects an advance of the indicator, means for returning the indicator to first position, and means mediateley connected to said indicator and movable therewith for effecting the operation of said indicator-returning means.

6. In a copy holder, a frame, a copy support, a sleeve arranged adjacent one of the edges of said support and journaled in said frame, a shaft in said sleeve concentric with said journals, a sprocket on said shaft, a chain driven by said sprocket, an indicator attached to the chain and overlying said copy support and means for turning the shaft a predetermined amount.

7. In a copy holder, a frame, a copy support, a sleeve arranged adjacent one of the edges of said support and journaled in said frame, a shaft in said sleeve concentric with said journals, a sprocket on said shaft, a chain driven by said sprocket, an indicator attached to the chain and overlying said copy support, means for turning the shaft a predetermined amount, a spring in said sleeve arranged to be placed in tension as said shaft is turned, and means on said chain for releasing said spring to rotate the shaft in the opposite direction.

8. In a copy holder, a frame, a copy support, a sleeve arranged adjacent one of the edges of said support and journaled in said frame, a shaft in said sleeve concentric with said journals, a sprocket on said shaft, a chain driven by said sprocket, an indicator attached to the chain and overlying said copy support, means for turning the shaft a predetermined amount, a spring in said sleeve arranged to be placed in tension as said shaft is turned, and means on said chain for releasing said spring to rotate the shaft in the opposite direction.

9. In a copy holder, a frame, a copy support on said frame, an indicator mounted upon said copy support, a ratchet wheel mounted upon said frame, means mediateley connecting the ratchet with the indicator, a key for turning said ratchet to advance said indicator across said copy support, a spring

resisting the said turning of the ratchet, a pawl engaging said ratchet when released by said key, and means on said indicator mounting for releasing said pawl from said ratchet, whereby said spring effects a recovery movement of said ratchet and said indicator.

10. In a copy holder, a frame, a copy support on said frame, an indicator mounted upon said copy support, a ratchet wheel mounted upon said frame, means mediateley connecting the ratchet with the indicator, a key for turning said ratchet to advance said indicator across said copy support, a spring resisting the said turning of the ratchet, a pawl engaging said ratchet when released by said key, means on said indicator mounting for releasing said pawl from said ratchet, whereby said spring effects a recovery movement of said ratchet and said indicator, means adapted to engage said released pawl during the said recovery movement and means for releasing said pawl engaging means at the end of said recovery movement.

11. In a copy holder, a frame, a copy support on said frame, an indicator mounted upon said copy support, a ratchet wheel mounted upon said frame, means mediateley connecting the ratchet with the indicator, a key for turning said ratchet to advance said indicator across said copy support, a spring resisting the said turning of the ratchet, a pawl engaging said ratchet when released by said key, means on said indicator mounting for releasing said pawl from said ratchet, whereby said spring effects a recovery movement of said ratchet and said indicator, and means for varying the movement of said ratchet by said key.

In testimony whereof, I have hereunto set my hand at San Francisco, California, this 2nd day of June, 1916.

WILLIAM B. RHOADS.
